UNITED STATES PATENT OFFICE.

EARL V. SHUE, OF MILWAUKEE, WISCONSIN, ASSIGNOR TO SHUE AIR RIFLE COMPANY, OF MILWAUKEE, WISCONSIN, A CORPORATION OF WISCONSIN.

AIR-GUN.

1,102,204.

Specification of Letters Patent. Patented June 30, 1914.

Application filed March 4, 1912. Serial No. 681,400.

To all whom it may concern:

Be it known that I, EARL V. SHUE, a citizen of the United States, and resident of Milwaukee, in the county of Milwaukee and State of Wisconsin, have invented new and useful Improvements in Air-Guns, of which the following is a description, reference being had to the accompanying drawings, which are a part of this specification.

10 This invention relates to air guns and has for its object to improve upon details of construction whereby an air gun may be strong and durable without becoming expensive to manufacture and whereby the 15 parts may be rendered more efficient in their operation.

Another object of the invention is to provide an air gun with a shot magazine and loader of novel construction which will permit of the magazine tube being rolled from sheet metal and which will cause the loader plug to be automatically locked in its normal position.

Another object of the invention is to provide a breech block rolled from sheet metal into tubular form and being of a thickness greater than the thickness of the plunger spring to take the thrust directly therefrom.

Another object of the invention is to provide a rear sight formed integral with the plunger cylinder and bent up therefrom.

Another object of the invention is to improve upon details of construction generally.

35 With the above and other objects in view the invention consists in the air gun as herein claimed and all equivalents.

Referring to the accompanying drawings in which like characters of reference indicate the same parts in the different views, Figure 1 is a side elevation of an air gun constructed in accordance with this invention; Fig. 2 is a longitudinal sectional view thereof; Fig. 3 is a sectional plan view thereof; Fig. 4 is a transverse sectional view thereof on the plane of line 4—4 of Fig. 1; Fig. 5 is a bottom view of the connecting means between the breech and stock; Fig. 6 is a transverse sectional view on the plane 50 of line 6—6 of Fig. 2 showing the loading plug; Fig. 7 is a detail view showing the loading plug in position for receiving a shot from the magazine and also showing the rear sight; Fig. 8 is a detail view of the 55 magazine; Fig. 9 is a plan view of the blank

from which the magazine tube is formed; Fig. 10 is a sectional plan view on the plane of line 10—10 of Fig. 4 showing the breech block in detail; Fig. 11 is a plan view of the blank from which the breech block is 60 formed; and, Fig. 12 is an end view of the breech block.

In these drawings 15 indicates the gun stock which is provided with cheek plates 16 at its forward end as usual between which is pivotally mounted a trigger guard plate 17 on a pivot bolt 18. A plunger cylinder 19 is carried by the trigger guard plate and has an opening through which the detent 20 projects to engage the hook 21 of the 70 plunger 22. The detent may be drawn from engagement with the hook 21 by the spring 75 pressed trigger 23, said trigger and detent having knuckle joints with each other and with the trigger guard plate 17 so as to form a toggle. The plunger 22 is pressed forwardly by a strong coil spring 24 contained within the plunger cylinder 19 and bearing at its rear end on a tubular breech block 25 which is firmly held within the cylinder and is of a tubular shape being rolled into form 80 from a blank of the shape shown in Fig. 11 having the slot 26 through which the detent projects and a notch 27 to receive the edge of the trigger guard plate.

85 The hook 21 of the plunger travels the length of a wire loop 28 which is connected at its ends to a pin 29 connecting the side cheeks 16 and when the gun is broken by swinging the stock on the pivot pin 18 the 90 said loop 28 draws the hook back until it is engaged by the detent 20 to cock the gun. The stock is returned to its normal position where it is held by spring ridges 30 on the cheek plates engaging similar ridges 95 31 on plates 32 which form the connecting means between the cylinder and the trigger guard plate.

At the forward end of the cylinder it has a metal plug 33 threaded within it and 100 threaded concentrically within this plug 33 is the barrel 34 preferably with a slightly tapering bore. A loading plug 35 is slidably mounted through the plug 33 and the ends of the cylinder and the barrel, as shown 105 in Fig. 7, with its flanged head lowermost and this loading plug has a transverse tapering feed opening 36 for receiving a shot from the magazine below the barrel and carrying it to the barrel, the sliding move- 110

ments of the loading plug between these two positions being determined by a flanged clip 37 mounted on the cylinder and projecting into a groove on the side with the 5 loading plug. The magazine is in the form of a tube bent from a blank of sheet metal shown in Fig. 9, one end portion being closed to complete the cylindrical formation and the other portion having its edges spaced 10 apart to form a slot between them through which the outstanding arm 38 of a follower 39 is adapted to pass. A coil spring 40 is contained within the closed portion of the magazine and bears at one end on the follower 39 and at the other end on an ear 41 which closes the end of the tube and forms the means for attachment of the magazine to the barrel by having a screw 42 passing therethrough. Notches 43 are 15 formed on the blank which stand opposite each other when the blank is rolled into tubular form and produce a circular opening through which shot may be introduced. The sides of the blank are also provided 20 with shoulders 44 which give to the slot an angular formation at its end to permit of the arm 38 of the follower being turned after the spring 40 is compressed and thus hold the follower beyond the opening 43 25 during the charging of the magazine. The other end of the slot is closed by a projection 45 on the blank which turns into a recess 46 at the opposite edge thereof and this end of the magazine fits within the 30 shouldered opening in the plug 33 through which the shot may pass into the opening 36 of the loading plug 35. When the magazine has been charged with shot the follower is turned out of engagement with the 35 shoulder at the end of the slot and under the action of its spring 40 it presses the row of shot along the magazine tube causing the 40 end shot to enter the opening 36 of the loading plug when said plug is in its lower position 45 shown in Fig. 7. A forward movement of the loading plug brings this opening 36 into register with the barrel and at the same time a notch 47 in the loading plug is engaged by the next shot and under the pressure 50 of spring 40 it serves to lock the loading plug in its upper position yieldingly. The same locking effect is produced when all of the shot have been fed from the magazine by the end of follower 39 which is 55 rounded to enter the recess 47 in the same manner as with the shot.

The rear sight 48 is desirably made integral with the cylinder, the latter being preferably of seamless tubing and having 60 the sight cut at the end thereof and punched and bent up therefrom and having the surplus metal cut away so as to make a neat fitting connection with the side cheeks 16.

In operation the gun is cocked by swinging 65 the stock on a pivotal pin 18 and causing

the loop 28 to draw the hook 21 against the action of spring 24 until it is engaged by detent 20 and then returning the stock to its normal position. This has caused the plunger 22 to be drawn to the position shown in Fig. 2. Then the gun is loaded by drawing the loading plug 35 downwardly to receive a shot from the magazine in its opening 36 and returning it to its upper position where it is held by the next shot or the follower 70 itself engaging the recess 47. In its upper position the loading plug 35 has its opening 75 36 in register with the bore of the barrel and upon the trigger being pulled to release the hook from the detent the spring 24 forces the plunger 22 forwardly and compresses the air within the cylinder 19 to forcibly 80 eject the shot through the barrel.

By means of the improved features of construction constituting this invention the air 85 gun is made strong and durable without liability to breakage or wear and still the expense of manufacture is low because of most parts being formed of sheet metal stampings.

What I claim as new and desire to secure 90 by Letters Patent is:

1. In an air gun, a magazine comprising a sheet metal tube formed of a blank of sheet metal bent into tubular form with its edges 95 spaced apart to form a slot between them, there being notches in opposite edges of the blank to register with each other to form an opening to receive a shot, and there being shoulders on the opposite edges of the blank 100 which when the blank is bent to the tubular form produce a lateral extension of the slot, a follower fitting within the tube, an arm on the follower traveling through the slot and adapted to engage the lateral extension of the slot, an ear on one end of the blank bent to close the end of the tube, and a spring confined within the tube and bearing at one end against the ear and at the other 105 end against the follower.

2. In an air gun provided with a barrel, a magazine, a loading plug slidably mounted across the barrel and the magazine and provided with an opening adapted to register with the magazine for receiving a shot therefrom when in one position and adapted to register with the barrel in another position, said loading plug being provided with a notch to be engaged by the end shot of the magazine for holding it in the last named position, and a spring pressed follower in 115 the magazine bearing on the shot.

3. An air gun, comprising a plunger cylinder, a plunger mounted therein, a hook on the plunger, a spring within the cylinder bearing against the plunger, a spring abutment formed of a triangularly shaped blank of sheet metal bent to a tubular form fitting 120 within the cylinder and being of greater thickness than the spring and having the 125

spring bearing thereagainst and adapted to have the hook pass therethrough, there being a notch in the rear end of the spring abutment, a trigger guard plate connected 5 with the cylinder and fitting within the notch, there being a slot in the spring abutment and the cylinder, and a trigger-operated detent passing through the said slot and engaging the hook.

10 4. In an air gun, a magazine comprising a sheet metal tube formed of a blank of sheet metal bent into tubular form with its edges spaced apart to form a slot between them, there being notches on opposite edges 15 of the blank to register with each other to form an opening to receive shot, and there being shoulders on the opposite edges of the blank which, when the blank is bent to the tubular form, produce a lateral exten- 20 sion of the slot, a follower fitting within the tube, an arm on the follower traveling through the slot and adapted to be engaged in the lateral extension of the slot, a spring seat at one end of the tube, and a spring 25 confined within the tube and bearing at one

end against the spring seat and at the other end against the follower.

5. In an air gun provided with a barrel, a magazine, a loading plug slidably mounted across the barrel and the magazine and provided with an opening adapted to register with the magazine for receiving a shot therefrom when in one position and adapted to register with the barrel in another position, said loading plug being provided with 30 a notch to be engaged by the end shot in the magazine for holding it in the last named position, and a spring pressed follower in the magazine bearing on the shot and having a rounded end to engage the notch of 35 the loading plug for holding it in the position in which its opening registers with the barrel when the last shot is contained therein.

In testimony whereof, I affix my signature, in presence of two witnesses.

EARL V. SHUE.
